UNITED STATES PATENT OFFICE

BRUCE M. WALKER, OF OAKLAND, CALIFORNIA.

MECHANICAL MOVEMENT.

Application filed October 16, 1925. Serial No. 62,841.

This invention relates to improvements in mechanical movements and has particular reference to means for changing the stroke of a connecting rod or pitman without stopping the machinery to which the same is connected.

Another object is to produce a device of this character which may be attached to the ordinary machinery now in common use 10 without materially altering the construction of the same.

Another object is to provide a device of this character which will not disturb the balance of the machinery.

15 A further object is to provide simple means for the controlling of the device.

Other objects and advantages will be apparent during the course of the following description.

20 In the accompanying drawings forming a part of this specification and in which like numerals are employed to designate like parts throughout the same,

Figure I is a side elevation of my device 25 as applied to the jack wheel of a well drilling rig,

Figure II is a fragmentary side elevation of my device,

Figure III is a top plan view thereof, 30 Figure IV is a fragmentary cross-sectional view of the gear arrangement, and

Figure V is a cross sectional view showing the sliding block carrying the pin thereon.

35 It is often advantageous to change the stroke in a piece of machinery without stopping the machinery. At the present time in the drilling of oil wells it is necessary to stop the drilling apparatus in order to move the pin to which the connecting rod is at-

40 tached farther from the bar so as to give a longer stroke. This stopping delays the drilling action and is therefore expensive. There are some instances where it is neces-

45 sary to have a slow pumping operation while another pump is operated at high speed, and it is to accommodate for these variances that I have provided my present invention.

50 In the accompanying drawings wherein for the purpose of illustration is shown a preferred embodiment of my invention, the numeral 5 refers to a jack wheel or fly wheel commonly employed in oil well drilling operations, which wheel is secured on a

shaft 6 mounted in suitable bearings 7 and 8 carried upon standards 9 and 11, respectively. This construction is common to all drilling operations.

It is customary to provide a crank which is keyed to the shaft 6 and to provide a plurality of holes in the crank into which the wrist pin to be later on described may be successively placed.

Instead of this construction, I propose to 65 attach to the shaft 6 as by a key 12, a block 13 which has chamfered edges 14 and 16. This block carries a head 17 through which shafts 18 and 19 project and extend parallel to the portion of the block. These shafts are 70 each provided with a gear as shown at 21 and 22, respectively, over which a chain 23 passes. This chain is also reeved over a gear 24 secured to a shaft 26 also passing 75 through the head 17 and carrying a bevel gear 27 upon its lower extremity.

This bevel gear 27 in turn meshes with gears 28 and 29. By referring to Figure 80 IV, it will be noted that the gear 28 is provided with an elongated hub 31, while the gear 29 is provided with a short hub 32 and that the gear 29 and its hub rotate upon the hub 31 of the gear 28. A brake band 33 is adapted to engage the hub 32, while a brake band 34 is adapted to engage the hub 31. 85 These brake bands are operated by control rods 36 and 37, respectively, and may be actuated from any convenient remote point.

By referring to Figures I and II, it will be noted that the shafts 18 and 19 are 90 screw-threaded and pass through a block 38, which block is slidable upon the block 13. This block carries a wrist pin 39 to which the connecting rod 41 is attached.

The result of this construction is that by 95 manipulation of either the rod 36 or 37, the block 38 may be caused to move toward or away from the axis of rotation as follows:—

Assuming that the rod 36 is actuated so 100 as to contract the brake band 33, the gear 29 will be held stationary with the result that the bevel gear 27 will rotate. This rotation will be transmitted through the shaft 26, gear 24, through chain 23 which will cause the shafts 18 and 19 to rotate and through their screw engagement with the block 38 will cause the same to move upon the block 13, depending upon the 105 direction of rotation of these screws the 110

2
crank pin 39 will be moved either toward or away from the axis of rotation of the shaft 6. By releasing the brake, rotation of the gear will cease and the block will be held securely in the newly adjusted position. By manipulating the other rod, as for instance, the rod 37, the band 34 will be tightened and the gear 28 will be held stationary. This will cause the rotation of the parts in a reverse direction, thereby causing the block 38 to move in a direction opposite to the movement before described.

It will thus be seen that the objects above set forth are accomplished in a simple and efficient manner.

It is to be understood that the form of my invention herewith shown and described is to be taken as a preferred example of the same and that various changes in the shape, size and arrangement of parts may be resorted to without departing from the spirit of the invention or the scope of the subjoined claim.

Having thus described my invention, I claim:—

In a device of the character described, a rotating shaft, a block keyed to said shaft, a second block slidably positioned on said first mentioned block, a pair of parallel screws positioned adjacent the first mentioned block and passing through said second mentioned block, the upper extremities of said screws being rotatably secured within the head of said first mentioned block, a gear secured to each of said screws, a chain extending over said gears, a pair of bevel gears rotatably secured on said shaft, a third bevel gear meshing with said first mentioned bevel gears, means associated with said last mentioned gear for imparting rotation to said chain, and means for securing said spur gears independently against rotation.

In testimony whereof I affix my signature.

BRUCE M. WALKER.
